THERMALLY INSULATED WALL STRUCTURE

John H. Thomas, New York, N. Y., assignor to
Richard Laurence Parish, New York, N. Y.

Application April 23, 1934, Serial No. 721,869

11 Claims. (Cl. 72—16)

My invention relates to wall structure and it has to do more particularly with thermally insulated walls.

One of the objects of my invention is to provide improved wall structure of the foregoing character which is of simple construction, is easy to construct and install, and is highly efficient in its ability to insulate against the transfer of heat by radiation, convection and conduction.

Another object is to provide improved means for insulating walls and particularly walls which include a wall-finishing surface such as plaster or the like.

Still another object is to provide means for thermally insulating a wall which eliminates the usual lathing and which is adapted to receive and support plaster or other wall-finishing materials.

An additional object is to provide an improved all-metal thermal insulation for walls which includes a plurality of spaced metallic sheets formed of a material of sufficient stiffness and thickness to withstand preformed shape and which possesses relatively low reflective characteristics when exposed to visible radiation and relatively high reflective characteristics when exposed to infra-red radiation, one of said sheets being so constructed and arranged that a wall-finishing material may be bonded thereto.

Further objects are to provide a substantially fire-proof wall; to provide warp-proof wall surfaces; to provide wall structure which is strong and durable and will afford substantially uniform insulation for practically the life of the structure insulated; to reduce, as in the case of homes or other buildings, heating costs, as well as aiding in the maintenance of a more uniform temperature within the enclosure defined by the wall structure; and to provide a wall structure where in the transfer of air therethrough by infiltration is reduced to the minimum.

Other objects and advantages will appear as this description progresses and by reference to the drawings wherein.

Figure 1 is an elevational plan view of one form of wall structure embodying my invention, certain of the parts being cut away to more clearly illustrate the relationship of the parts.

Fig. 2 is a section taken substantially on line 2—2 of Fig. 1;

Fig. 3 is a section taken substantially on line 3—3 of Fig. 2; and

Fig. 4 is a fragmentary view similar to Fig. 3 showing another form of my invention.

The wall structure illustrated in the drawings is of a character which may be employed in va-

rious forms of building structures. It is to be understood, however, that the invention is not limited to this particular form of structure, but it has utility in various other structures wherein similar conditions of use are to be met. Also, while the drawings show my invention applied to an outer wall structure, it may be equally well applied to inner walls including ceilings and floors of buildings and other enclosures.

The wall structure shown in the drawings includes vertical stud members 10 and horizontal cap and sill members 11 and 12 which define the edges of a plurality of wall spaces 13 along each wall. The outer part of each space 13 is covered by the usual boxing 14 and an outer finishing surface 15 which may take the form of weatherboarding or any other suitable structure.

The inner side of each space 13 is covered by a wall unit 17—21 with which this invention is concerned. This unit includes a metallic sheet 16 which supports a wall-finishing covering 17 which, preferably, takes the form of plaster. It is to be understood that, although various forms of plaster are well suited as the finishing covering, other forms of material which may be secured to the sheet 16 may be used in certain instances without departing from my invention.

The plaster covering 17 is secured to the metallic sheet 16 in the following manner: a plurality of projections 18 are struck outwardly from and at an angle with respect to the outer face of the sheet 17, thereby providing openings 19 in such sheet inwardly of and directly behind the projections 18, which are disposed fairly close together. The projections 18 are arranged in horizontal rows and the projections in adjacent rows are staggered with respect to each other (Fig. 1). The plaster 17 is applied to the sheet in the usual plastic condition. The projections 18 are of such size and so spaced apart that, when they are imbedded in the plaster, the plaster covering, even in its original plastic state, is supported in its intended position. A small portion of the plastic plaster flows through the openings 19, as indicated at 20, thereby providing an additional interlocking bond between the sheet 16 and the plaster covering 17. This bond is of such a character that, when the plaster finally sets and hardens, it is firmly supported by the metallic sheet 16 against both vertical and outward displacement.

It will be seen from the foregoing that the metallic sheet 16 eliminates the use of the lathing heretofore employed; and this sheet, while supporting the plaster, also serves to reduce to the

minimum the transfer of air through the plaster by infiltration.

The metallic sheet 16 also plays a part in insulating against the transfer of heat through the wall space 13 by radiation, convection, and conduction. To that end, the sheet 16 is formed of a metallic material which possesses relatively low reflective characteristics when exposed to radiation of wave lengths within the visible portion of the electromagnetic spectrum and relatively high characteristics when exposed to radiation of longer wave lengths than the visible portion of the electromagnetic spectrum, or a material of the character disclosed in Letters Patent No. 1,910,703, granted to Joseph M. LeGrand, on May 23, 1933. Such a material possesses relatively low reflective efficiency when exposed to visible radiation and relatively high reflective efficiency when exposed to infra-red radiation as is the case in the use of structure embodying my invention. Commercial black steel well serves this purpose and I, therefore, preferably, form the sheet 16 from such material, which is of sufficient stiffness and thickness to withstand pre-formed shape and to readily support the plaster covering 17.

In providing against the transfer of heat through the space 13 by radiation, convection, and conduction, I mount another metallic sheet 21 in the space 13. The sheet 21 is mounted closer to the metallic sheet 16 than to the outer wall unit 14-15 so as to divide the space 13 into a plurality of variable-depth spaces 13^a and 13^b, the shallower of which is the space 13^b between the sheets 16 and 21.

The metallic sheet 21 is, preferably, formed of the same material as the sheet 16 and it is also of sufficient thickness and stiffness to retain pre-formed shape. Its surface is preformed to provide therein a plurality of angular and intersecting plane surfaces 22 which afford increased insulation effect. Ribs 23 are provided at the intersections of the plane surfaces 22 to add strength and rigidity to the sheet 21 and to prevent detrimental vibration thereof.

The metallic sheet 21 is supported by the vertical stud members 10 in substantially parallel relation with respect to the sheet 16. The body of this sheet 21 is of such dimensions as to extend throughout the length and width of the space 13. It is secured to the stud members 10 by offset side edge flanges 24 which overlap the side edges of the stud members 10 beneath the side edges of the sheet 16. The offset portions 25 of the flanges 24 determine the spacing of the sheets 16 and 21 and this offsetting may be varied to suit variable width wall spaces and various conditions of use, all without departing from my invention. For instance it will be noted that the spacing nearest the inside of the wall is less than that nearest the wall's outside surface. This is in accordance with the teachings in the above-mentioned Le Grand patent, where it is shown that greater insulation efficiency results when the narrower space is nearest the hot side of the wall—and in this instance, since the temperature variations are greater in winter and the wall is designed primarily for the saving of fuel at that season, the hot side is considered to be the inside of the wall.

In the installation of the structure so far described, the inner sheet 21 may be first inserted in place, after which the sheet 16 is applied, and both of these sheets are simultaneously secured to the stud members 10 by fastening devices 26

passing through the side edges of both sheets at spaced points therealong. Both of these metallic sheets, preferably, extend throughout the height of the space 13 and the inner sheet 21 is of such length that its opposite ends snugly abut the cap 5 and sill members 11 and 12 (Fig. 2). In this way the substantially parallel air spaces 13^a and 13^b are substantially sealed apart from each other.

The spaces 13 are usually of comparatively narrow width and, in certain cases, I may employ 10 wall-forming metallic sheets 16 of sufficient width to cover two or more of these spaces. An arrangement of that character is shown in Fig. 4. In that case, the inner wall-forming sheet 21 which supports the plaster 28 is of sufficient width to span 15 two successive spaces 29. If desired, a single sheet like sheets 21 may be employed for each space 29 or a single sheet 30 may be used for two (or more) successive spaces 29. In either case, the sheets 21 and 30 are, preferably, formed of 20 the same material, and correspond in other respects, to the sheets 16 and 21; except, however, where a single sheet 30 is employed for two spaces, such sheet is provided with a vertically-extending offset portion 31 providing a pocket 32 of 25 such size and shape as to snugly receive the side edge portion of the upright stud member 33. If a single sheet 30 extends into more than two spaces 29, the desired number of pockets 32 are provided to accommodate additional stud members 33. In this form, the sheets are applied and secured by fastening devices 34, after which the plaster 28 is applied and permitted to harden and set to complete the finished wall surface.

It is believed that the operation and advantages of my invention will be fully understood from the foregoing. By employing metallic sheets formed of the material hereinabove specified and arranged as described the transfer of heat by radiation, convection, and conduction is practically reduced to the minimum. Furthermore, my invention provides a simple and inexpensive insulation means which eliminates the use of the usual lathing and which, in turn, serves to directly support the plaster or other wall-finishing material. This arrangement gives to the user, at the minimum of cost, a substantially permanent wall structure which affords high insulation efficiency for practically the life of the structure insulated. My invention also, through its insulation ability and by minimizing air infiltration, reduces the cost of heating homes, buildings and other enclosures, as well as aiding in the maintenance of more nearly uniform temperature condition. Wall units embodying my invention may be readily shipped, stored and installed.

It will be understood that while I have shown and described only two forms of my invention, other changes in details and arrangement of parts may be made without departing from the spirit and scope of my invention as defined by the claims which follow. For example, without limiting the foregoing generality, a greater number of metallic sheets may be mounted in the wall 65 spaces in spaced relation with respect to each other and the inner and outer walls which sheets may be provided with edge flanges that may be readily secured to the upright stud members. Also, the projections 18 instead of being struck 70 out from the metallic sheets 16 and 27 may, if desired, be separate members secured to the sheet by welding or otherwise.

I claim:

1. In structure of the class described, an outer wall, support members therefor, an inner wall

secured to said support members said inner wall comprising a sheet of ordinary metal having members projecting from one face thereof, a wall finishing covering carried by said sheet and interlocked with said projected members, and another metallic sheet of steel having a high heat-reflectivity surface and mounted in the space between said two walls in spaced and substantially parallel relation with respect thereto, said metallic sheets being spaced substantially closer together than said outer wall and second-named metallic sheet.

2. In structure of the class described, an outer wall, support members therefor, an inner wall secured to said support members, said walls and support members forming a plurality of separate spaces in substantially the same plane, said inner wall comprising a sheet metal section having members projecting from one face thereof, a wall finishing covering carried by said section and interlocked with said projected members, and a metallic sheet mounted in each of the spaces between said two walls in spaced and substantially parallel relation with respect to said walls, both said metallic section and said metallic sheet being formed of a steel material having high heat-reflectivity and having contacting portions of their surfaces fastened at common points to said support members.

3. In structure of the class described, an outer wall, support members therefor, an inner wall secured to said support members, said inner wall comprising a sheet of shape-retaining commercial black steel having members projecting from one face thereof, a wall finishing covering carried by said sheet and interlocked with said projected members, and another commercial black steel sheet having a surface of high heat-reflectivity and mounted in the space between said two walls in spaced and substantially parallel relation with respect thereto.

4. In structure of the class described, means forming wall spaces to be insulated and including a series of vertical and spaced supporting members, an outer wall member carried by said supporting members, and an inner wall carried by said supporting members, said inner wall comprising a sheet member, a wall-finishing covering for said sheet member, means between said sheet member and said covering for bonding the same together as a unit, and another sheet member mounted in each of said spaces and secured to said supporting members in spaced and substantially parallel relation with respect to said first sheet member and said outer wall and constructed and arranged to divide each of said spaces into a plurality of air chambers substantially sealed apart from each other, both of said sheet members being formed of a comparatively thin steel material of sufficient thickness and stiffness to retain preformed shape and which has higher reflective characteristics when exposed to infra-red radiation than when exposed to visible radiation.

5. In structure of the class described, an outer wall, support members therefor, an inner wall secured to said support members, said inner wall comprising a metallic sheet, a wall-finishing covering, said metallic sheet being provided with uni-directional means for securing said covering thereto, another metallic sheet mounted in said space between said two walls in spaced and substantially parallel relation with respect thereto, said latter metallic sheet being also fixedly se-

cured to said support members along the edges of the former whereby said space is subdivided into a plurality of air spaces substantially sealed apart from each other.

6. In structure of the class described, an outer wall, support members therefor, an inner wall secured to said support members and defining a substantially rectangular space of comparatively shallow depth, said inner wall comprising a metallic sheet, a wall-finishing covering thereon, means for securing said covering to said metallic sheet, and another metallic sheet mounted in said space between said two walls in spaced and substantially parallel relation with respect thereto, said second metallic sheet having a body portion of substantially the length and width of said space and laterally-flange parallel-surface means around the edges thereof adapted to be fixedly secured to said support members to subdivide such space into a plurality of substantially parallel air spaces substantially sealed apart from each other, both said metallic sheets being fastened to the support members by common fastening means.

7. In structure of the class described, means forming a wall space, said means including a wall unit comprising a metallic sheet having a plurality of projections struck therefrom and providing a like number of openings therein, and a wall-finishing covering mounted upon said metallic sheet on its side having said projections, said covering being of a character adapted to be applied in a plastic condition and to finally set and harden to provide a finished surface, said covering in its plastically-applied condition being adapted to embeddedly receive said projections and to flow through said openings to fixedly bond said covering to said metallic sheet, and all said projections being so formed that they project upwardly from the bottoms of said openings to facilitate passage of said plastic covering through said openings.

8. In structure of the class described, means forming a wall space, said means including support members and a wall unit secured thereto and comprising a metallic sheet having a plurality of projections struck therefrom providing a like number of openings therein from the bottoms of which said projections extend upwardly, and a wall-finishing covering mounted upon said metallic sheet on its side having said projections, said covering being of a character adapted to be applied in a plastic condition and to finally set and harden to provide a finished surface, said covering in its plastically-applied condition being adapted to embeddedly receive said projections and to flow through said openings to fixedly bond said covering to said metallic sheet, and another and imperforate metallic sheet mounted in said space in spaced and substantially parallel relation with respect to said first metallic sheet, both of said metallic sheets being formed of a material of sufficient thickness and stiffness to retain preformed shape and possessing higher reflective characteristics when exposed to infra-red radiation than when exposed to visible radiation, and means for fixedly securing both said sheets to said support members.

9. In structure of the class described, successive support members and wall means forming a plurality of spaces all in substantially the same plane, said means including a wall unit comprising a steel sheet of high heat-reflectivity adapted to cover a plurality of said spaces, a wall-finishing covering, means by which said covering is se-

- curely bonded to the outermost face of said metallic sheet, and another single metallic sheet of substantially the same material and outline dimensions of said first sheet spanning the spaces covered by said first sheet in spaced relation to the latter and sub-dividing each of the spaces covered by said first sheet into a plurality of separated air spaces, and common means fixedly securing both of said sheets to said support members.
10. In structure of the class described, an outer wall, upright supports therefor, a steel shape-retaining sheet of high heat-reflectivity secured to said supports and serving as an inner spaced wall member, said supports dividing the space between said walls into a plurality of successive spaces all in substantially the same plane, another metallic sheet secured to said supports within said space in spaced relation to said inner wall metallic sheet, said second sheet extending laterally past one or more of said supports into and spanning a plurality of said successive wall

spaces to divide each of the latter into a plurality of air spaces, and means for fixedly securing said metallic sheets to said supports.

11. In structure of the class described, an outer wall, an inner wall mounted in spaced relation to said outer wall, said inner wall comprising a metallic sheet of sufficient stiffness and thickness to withstand preformed shape and having a plurality of rows of projections extending from one face thereof, said projections being arranged in rows with the projections in adjacent rows staggered with respect to each other, a wall finishing covering upon said sheet and interlocked with said projections, and another and imperforate metallic sheet mounted between 15 and in spaced parallel relation with respect to said inner and outer walls, said latter metallic sheet being of a character possessing relatively higher reflective characteristics when exposed to 20 infra-red radiation than when exposed to visible radiation.

JOHN H. THOMAS.
